his Attorney

UNITED STATES PATENT OFFICE.

THOMAS J. PICOS, OF EL MONTE, CALIFORNIA.

LINER PULLER.

Application filed March 17, 1925. Serial No. 16,263.

This invention relates to a liner puller intended primarily for use in removing liners from pump cylinders, and the like.

It is an object of this invention to provide 5 a liner puller for a pump operable by the power employed for operating the pump.

Another object of this invention is to provide a liner puller which is operable to drive a liner out of its seat.

10 Another object of the invention is to provide a device of the character above referred to which is simple, effective and practical in construction.

The various objects and features of my 15 invention will be best and more fully understood from the following detailed description of a typical preferred form of the invention throughout which description reference is had to the accompanying drawings 20 in which:

Fig. 1 is a sectional view of a typical form of a direct acting steam pump showing the device provided by my invention in operating position in the liner of the pump 25 cylinder.

Fig. 2 is an enlarged detailed sectional view of the device provided by this invention showing it in operating position in a liner.

30 Fig. 3 is a transverse section taken as indicated by line 3—3 on Fig. 2 and

Fig. 4 is the detailed transverse section view taken as indicated by line 4—4 on Fig. 2.

35 The cylinders of pumps and various like mechanisms are commonly provided with liners intended to be removed and finished or replaced from time to time. It is common practice to force such liners into place

40 in the cylinders and to provide packing means to make them tight when in place. In practice great difficulty is often experienced in removing liners from cylinders as they are frequently seated very tightly 45 and become set so that it is very difficult to dislodge them.

The device provided by this invention is broadly applicable to removing liners in various mechanisms. It is particularly suited, however, for the removal of pump 50 liners. Direct acting steam pumps being

the most common type of pumps in common use, I have herein set forth my invention in combination with this particular type of pump, it being understood that such 55 reference is merely for purpose of illustration and to facilitate a practical understanding of the invention and is not to be considered as limiting the scope or range of application of the invention. 60

The pump illustration in Fig. 1 of the drawings being a typical and simple form of direct acting steam pump includes, generally, a steam cylinder 10, pump cylinder 11, a suitable frame 12 carrying the cylinders, 65 a piston rod 13 extending between the cylinders, a piston 14 on the rod 13 in the steam cylinder 10, and various other parts common to mechanisms of this general character. I have illustrated a pump in which the 70 pump cylinder 11 is provided with a typical liner 15 and have, in the drawings, illustrated the liner puller provided by my invention arranged in the liner 15 in place of the piston which normally operated therein. 75

In accordance with standard practice I have illustrated the pump end of the piston rod 13 provided with a reduced part 16 to carry the pump piston. With this construction the piston rod presents a shoulder 17 against 80 which the piston is held when in place on the rod, the outer end of the reduced part 16 being threaded at 16^a to receive a nut which operates to clamp the piston against the shoulder 17. The arrangement of the 85 pump piston on the rod is not illustrated in the drawings, however, this construction is employed in practically every pump of this character and is familiar to those skilled in the art. 90

The construction provided by my present invention is intended primarily to engage or grip the cylinder liner 15 and to be actuated by or through the operating means of the pump, in this case by the piston rod 13. 95 The form of the invention illustrated in the drawings, includes, generally, a body 20 adapted to be applied to and operated by the piston rod 13, and means 21 carried by or connected with the body 20 and adapted 100 to a grip of the cylinder liner 15.

The body is preferably tubular in form

and is provided with a longitudinal opening 22 sufficiently large to freely pass the reduced part 16 of the piston rod. The outside of the body is provided with screw threads 23 adapted to carry and hold the liner engaging means 21. The body 20 is adapted to be arranged on the reduced part 16 of the piston rod between the shoulder 17 and an abutment, for instance a nut 24 applied to the screw thread part 16^a at the outer end of the reduced part 16. The body 20 is proportioned and the shoulder 17 and nut 24 are related, so that a certain amount of longitudinal movement may take place between the rod and body. The particular amount of movement desired between the rod and body may vary and may be regulated by varying the position of the nut 24 on the screw thread part 16^a. When the device is operated, as will be hereinafter described, the piston rod is moved relative to the body to bring the shoulder into engagement with the inner end of body 20 and thereby force or drive the body outwardly with relation to the pump cylinder of liner. In order that the impact of the shoulder 17 driving the liner may not damage the shoulder 17, or the end of the liner, it is desirable to provide means between the shoulder and the end of the body to protect them. In the form of the invention illustrated in the drawings I have shown a removable cap 26 on the end of the body 20 and have also shown a protecting ring 27 arranged on the reduced part 16 of the rod in engagement with the shoulder 17. With this construction the wear or distortion caused by operation of the device is taken by the parts 26 and 27. These parts being comparatively small and simple in construction may be replaced with very little expense.

In accordance with the broader application of my invention the liner engaging means 21 may be varied in its mode of operation and construction it being essential only that this means be such as to effectively and securely engage or grip the pump liner so that the liner is moved with the body 20. In accordance with the preferred form of my invention the liner engaging means operates to frictionally engage within the liner and includes, generally, a wedge member 30 and a plurality of slips 31. The wedge member is connected to the body 20, it being preferred to mount it directly on the body, for instance, to screw thread it on the body as clearly shown in Fig. 2 of the drawings. The wedge faces 32 which carry the slips 31 are provided with ribs 33 which operate in sockets 34 in the slips to retain the slips in position. The body 30 is, of course, disposed longitudinally of the cylinder liner and the wedge faces 32 extend longitudinally of the body and are inclined or inwardly divergent, as clearly shown in

Figs. 2, 3, and 4 of the drawings. The inner surfaces of the slips 31 are disposed to properly fit the wedge surfaces of the wedge member, while the outer surfaces 36 of the slips are curved to conform to the interior or inner surface 37 of the liner. In practice I prefer to provide the outer surfaces 36 of the slips with a plurality of transverse depressions 50 as I find this increases the gripping power of the slips and I prefer to form the slips of material which is softer than the liner so that they do not cut or damage the surface of the liner.

As means for operating or urging the slips into position with relation to the wedge so that they grip the interior of the liner I may provide a spring 40 in connection with each slip to normally urge it inwardly with relation to the wedge member. In the particular construction shown in the drawings springs 40 are arranged between the slips 31 and a flange member 41 retained on the outer end of the body 20 by a nut 42. The springs 40 are helical compression springs arranged under compression between the flange member 41 and slips 31. The amount of compression of the springs and therefore the pressure with which the slips are operated may be regulated by adjustment of the nut 41 on the body. With the construction which I have just described the device can be moved freely inwardly in the liner to the desired position but as soon as it is started outwardly in the liner the slips grip the liner to prevent the outward movement. In practice it is desirable to provide one or more of the slips with a screw threaded opening 70, or the like, to receive a screw threaded rod or the like, if it is desired to release the device when in position in the liner. In the construction shown in the drawing the flange member 41 is provided with openings 71 so that rods, or the like, can be inserted into the liner from its outer end to engage the openings 70 in the slips.

In operating the device it is applied to the piston rod in the manner shown throughout the drawings so that the body 20 is carried between the shoulder 17 and nut 24 with provision for the desired amount of movement of the rod relative to the body. With the device in place on the rod it may be moved inwardly to the desired position in the liner by suitable operation of the steam cylinder. With the device in position such as shown in Fig. 1 of the drawings, its various parts are related as shown in Fig. 2, the slips 31 being in position to grip the liner and the piston rod and body 20 are related so that the nut 24 is in engagement with the outer end of the body, while the shoulder 17 is spaced from the inner end of the body. The parts thus set ready for operation, steam may be admitted into cylinder 10 to move the shoulder 17, or the ring 27, into engagement

with the inner end of the body, or cap 26, it being preferred to apply pressure gradually to the body to make certain that the slips are properly gripping the liner. By applying 5 pressure gradually to the body the liner may be forced out of the cylinder, however, it is usually necessary to return the parts to the position shown in Fig. 2 and to apply steam to cylinder 10 to move the ring 27 quickly 10 into engagement with the cap 26 to impart a blow to the body. If the liner is not dislodged by a single blow the operation may be repeated and the force of the blows varied until the liner is removed. When the liner 15 has been dislodged the device may be easily released from the liner and removed from the piston rod. From the foregoing description it will be apparent that the various degrees of pressure and impact may be obtained 20 through the mode of operation just described and that the device when properly operated will quickly and effectively dislodge a cylinder liner even though it may be very tightly seated.

25 Having described only a typical form and application of my invention I do not wish to limit myself to the particular details hereinabove set forth, but wish to reserve to myself any changes or variations that may appear 30 to those skilled in the art, or fall within the scope of the following claims.

Having described my invention, I claim:

1. A device for use in a cylinder having a liner and a rod extending into it, said device 35 including a body, means for connecting the rod and body for limited relative movement, and means for connecting the body and liner including a wedge carried by the body and a plurality of slips operated by the wedge to 40 grip the liner.

2. A device for use in a cylinder having a liner and a rod extending into it, said device including a body, means for connecting the rod and body for limited relative movement, 45 and means for connecting the body and liner including a wedge member carried by the body, slips arranged to be operated by the wedge member, and means normally tending to operate the slips to cause them to grip the liner.

3. A device for use in a cylinder having a liner and a rod extending into it, said device including a body, means for connecting the rod and body for limited relative movement, 55 and means for connecting the body and liner including a wedge member carried by the body, slips operable by the wedge member, and spring means normally urging the slips to position to grip the liner.

4. A device for use in a cylinder having a liner and a rod extending into it, said device including a body, means for connecting the rod and body for limited relative movement, and means for connecting the body and liner including a wedge member carried by 60

the body, slips operable by the wedge member, and spring means normally urging the slips to position to grip the liner, the spring means including springs each having one end held stationary relative to the body 70 and the other end engaging a slip.

5. A device for use in a cylinder having a liner and a rod extending into it, said device including a body, means for connecting the rod and body for limited relative movement, 75 and means for connecting the body and liner including a wedge member carried by the body, slips operable by the wedge member, and spring means normally urging the slips to position to grip the liner, the spring 80 means including a stop member carried by the body and springs arranged between the stop member and slips.

6. A device for use in a cylinder having a liner and a rod extending into it, said device 85 including a body, means for connecting the rod and body for limited relative movement, and means for connecting the body and liner including a wedge member screw threaded on the body, slips operable by the wedge 90 member, and spring means normally urging the slips to position to grip the liner, the spring means including a stop member carried by the body and springs arranged between the stop member and slips. 95

7. A device for use in a cylinder having a liner and a piston rod extending into it, said device including a body, means for connecting the body and rod for limited relative movement whereby the body can be jarred by operation of the rod and liner engaging means carried by the body, said connecting means including a slidable connection between the body and rod and stop means on the rod to limit the sliding movement. 100

8. A device for use in a cylinder having a liner and a piston rod extending into it, said device including a body slidably fitting the rod, means on the rod to limit the sliding movement between the rod and body so that the body can be jarred from the rod, and means for connecting the body with the liner. 110

9. A device for use in a cylinder having a liner and a piston rod extending into it, said device including a body slidably fitting the rod, means on the rod to limit the sliding movement between the rod and body so that the body can be jarred from the rod, and slips for connecting the body with the liner. 115

10. A device for use in a cylinder having a liner and a piston rod extending into it, said device including a body to be mounted on the rod, means whereby the body can be jarred by operation of the rod, and means for connecting the body with the liner. 120

11. A device for use in a cylinder having a liner and a shouldered piston rod extending into it, said device including a nut applied to the rod in spaced relation to the shoulder on the rod, a body mounted on the 130

rod slidable between the shoulder and nut, and means for connecting the body with the liner.

12. A device for use in a cylinder having a liner and a shouldered piston rod extending into it, said device including a nut applied to the rod in spaced relation to the shoulder on the rod, a body mounted on the

rod slidable between the shoulder and nut, means for protecting the shoulder, and means for connecting the body with the liner.

In witness that I claim the foregoing I have hereunto subscribed my name this 17th day of February, 1925.

THOMAS J. PICOS.
